UNITED STATES PATENT OFFICE.

WILLIAM H. VOORHEES, OF COLUMBUS, OHIO.

DESIGN FOR A LIGHT FOR ILLUMINATED SIGNS.

SPECIFICATION forming part of Design No. 33,192, dated September 11, 1900.

Application filed April 28, 1900. Serial No. 14,765. Term of patent 14 years.

To all whom it may concern:

Be it known that I, WILLIAM H. VOORHEES, a citizen of the United States, residing at Columbus, in the county of Franklin and 5 State of Ohio, have invented and produced a new and original Design for Lights for Illuminated Signs, of which the following is a specification, reference being had to the accompanying drawings, forming part thereof.

Figure 1 is a side elevation; Fig. 2, a vertical section on line xx of Fig. 1, and Fig. 3 a horizontal section on line yy of Fig. 1.

As shown in the drawings, my design consists of an annular groove 1, a regular rounded 15 head 2, and a conical body 3 of regular out-

line. The groove is located intermediate the head and the conical body and defines their terminations.

Having described my invention, what I claim as new, and desire to secure by Letters 20 Patent, is—

The design for a light for illuminated signs, as herein shown and described.

In testimony whereof I affix my name in presence of two witnesses.

WILLIAM H. VOORHEES.
